CLAIM

The ornamental design for a pair of handle pockets for a lift and slide fenestration, as shown and described.

DESCRIPTION

FIG. 1 is a front perspective view of a pair of handle pockets for a lift and slide fenestration in accordance with our new design.

FIG. 2 is a front elevational view thereof; and,

FIG. 3 is a top plan view thereof.

The heavy wavy broken lines that appear at the ends of the pair of handle pockets for the lift and slide fenestration represent the bounds of the disclosure and form no part of the claimed design.
